MULTIPLE SELECTOR SYSTEM

Yoshito Watanabe, Kinukake-cho, Suma-ku,
Kobe, JapanApplication January 17, 1935, Serial No. 2,157
In Japan March 12, 1934

3 Claims. (Cl. 177—353)

The present invention relates to improvements in an automatic telegraph receiving system claimed in my United States patent application Serial No. 2,156, filed January 17, 1935, and refers more particularly to a multiple system having a movable controller provided with a series of contact making elements and movable one section at a time, and a selective means removing said contact making elements selectively in response to different electric signals according to any suitable telegraphic code and adapted to cause said selectively controlled contact making elements to trace separate tracks when said movable controller travels; the present invention is characterized by the fact that the sets of the groups of contact switching elements arranged to correspond with the arrangement of said controlled rollers are provided in a large number for several different signals, so that if there is any one among these sets which corresponds to an arriving signal, it is selected to complete its own alarming circuit; and also that directly after the operation of one set another signal is received and the corresponding set is operated in turn. The object of this invention is to enable a single system to serve as several different receiving systems and to receive messages independently of one other. The mechanical structure of the selector used in the present invention is described more clearly in my British Patent No. 436,343, or my French Patent No. 791,554, which correspond to the application previously mentioned.

Referring to the accompanying drawings,

Fig. 1 is a plan of the main part of a multiple automatic telegraph receiving machine constructed according to the present invention; the groups of contact members disposed on the fixed frame are not shown in this figure.

Fig. 2 is an end view of a rotatable controller partly in section;

Fig. 3 is a section along the line 3—3 of Figure 1 and shows the superposed contact members;

Fig. 4 is a development showing an example of the arrangement of the contact making elements;

Fig. 5 is a development showing as examples several arrangements of groups of contact switching elements;

Fig. 6 is an across-the-line-wiring diagram of the whole system.

Referring to Figs. 1 to 3 a rotatable controller formed by mounting a group of slidable contact making rollers 4 upon studs 3 arranged between opposite side plates 2 with equal space between each stud and an adjacent one to form a squirrel cage, is adapted to rotate one section forward for

every element of a signal according to the Morse code, and also to rotate the rollers 4 at a certain selecting line to a predetermined side according to the kind of each element. Groups of switches to complete the contacts by being operated by the rollers are arranged to correspond with the expected signal and are connected to an alarming electric circuit, so that upon coincidence with an arriving signal they may be operated. Now, in the present invention as shown in Fig. 3, sets of several contact switching elements are provided for many different signals and are connected to their respective alarming circuits equipped with electric magnets for operating electric lamps and other alarming devices said magnets having auxiliary contacts for self-holding in order that when a set of contact point arrangement is operated by the arrival of the corresponding signal the alarming may be continued, unless said magnets are opened, and when another signal follows the above one, substantially the similar operation is caused.

In the drawings, 1 is a fixed frame of drum type secured to the base of the machine at either side of the rotatable body 2 and forms a bearing 7 for the shaft 8 of the rotatable body. At the periphery of said fixed frame 1 holes 9 for attaching the contact switching elements are provided at the position corresponding to that of each stud 3 of the rotatable body 2. 5 are several arc-shaped partitions starting from a section next to the selecting line of the contact making rollers. They are combined with suitable holding plates 6 to partition the positions of the forward movement of the rollers into three tracks; i. e., right, middle and left tracks, along the outer periphery of a row of the studs 3. *s* and *m* are the levers pivoted to the base at pivots *f*₁ and *f*₂ and also partially fitted to the ends of the rods *u*₁ and *u*₂ connected to the armatures *h*' and *g*' of magnets *h* and *g* respectively, so as to remove the roller 4 to correspond with a "letter space" and "dash" marks according to Morse code. They are provided at their ends with pawls *s*' and *m*' consisting of springs. *k* and *l* are push rods having the end pawls mesh with the teeth of the ratchets *w* and *w*' fixed to the shaft 8 of the rotatable body 2, while their other ends *v*₁ and *v*₂ are fitted to levers or rods *10* and *10*' pivoted at their ends *f*₃ and *f*₄ respectively, said rods *10* and *10*' being fitted to the ends of the rods *u*₃ and *u*₄ connected with the armatures *i*' and *j*' of the electric magnets *i* and *j*.

Since it is undesirable to have the two selecting levers operate upon a roller of the same sec-

tion, these levers are provided with side apertures and are guided to move horizontally, as described more clearly in my co-pending patent application, Serial No. 2,156, filed January 17, 1935.

- 5 In Figure 6, A, B, D, E, *h*, *g*, *i*, *j* show electric magnets; *K*₁ is a switch to change an aerial line *N* in a radio for a wire telegraph line *T*; *K*₂ is a by-path switch; *K*₃ is a controlling switch with 10 an auxiliary contact *c* which opens when the switch is closed and which closes when the switch opens; *R*, a receiving relay; *M*, an amplifier and amplitude regulator; *C*₁ and *C*₂ are electric sources; *F*₁ to *F*₅ illustrate diagrammatically 15 the arrangement of several series of multiple contacts on the fixed frame 1; *q*₁ to *q*₆ are relays which are provided with normally open and instantly closed contacts *n*₁ to *n*₆, normally closed and instantly open contacts *t*₁ to *t*₆ and holding 20 contacts *e*₁ to *e*₆; *L*₁ to *L*₆ are signalling lamps; *Z* and *Z*₁ are buzzers.

25 The relay *A* is provided with an electric contact *c*₁, which is a normally open and instantly closed contact, a normally open time delay closing contact *c*₂, and a normally closed and instantly opening contact *c*₆. The electro-magnets *B*, *D* and *E* are provided with normally open and instantly closed contacts *c*₃, *c*₄, and *c*₅, respectively, while the electro-magnets *i* and *j* have push rods 30 *k* and *l*, which in cooperation with the ratchets *w* and *w'* fixed to the shaft of the rotatable body 2 move the rotatable body 2 forward by one step each time the magnets *i* and *j* are energized. As 35 stated above, the electro-magnets *h* and *g* have selective levers *s* and *g*, respectively, which shift the contact-making rollers 4 selectively when each magnet is operated, the lever *s* being provided with electric contacts *a* and *b*, which are closed when it operates.

40 In the arrangement shown in Figure 6, if the switch *K*₁ is closed on the side of the antenna 11 or the wire telegraph line 12 and the switch *K*₂ is kept closed and an electric signal corresponding to the 'dot' mark is received, the relay *R* is 45 energized so that it attracts its armature 20 and closes the contact 21. Then the circuit of the electromagnet *A* is completed, said circuit comprising *C*₁, the lines 22, 23, and 23', the coil of the electro-magnet *A*, the line 24, the closed contact 21, and the lines 25, 26, and 27; then the 50 electro-magnet *A* is operated.

If, however, the incoming signal is a 'dot' mark, the current flows through the coil of the magnet *A* for a very short time only, and, therefore, 55 merely closes and opens the contacts *c*₁ and *c*₆, respectively, without closing the time delay contact *c*₂. Then the circuit of the electro-magnet *j* is completed, said circuit including the battery *C*₁, the line 22, the battery *C*₂, the lines 28, 29, 60 and 30, the closed contact *c*₁, the line 31, the coil of the electro-magnet *j*, and the lines 32, 26, and 27. Thus the electro-magnet *j* moves the controller 2 forward by one step through the ratchet *w'* by means of a push rod *l*.

65 However, upon receiving an electric signal corresponding to the 'dash' mark, the relay *R* attracts its armature 20 to close the contact 21 for a comparatively long time, and consequently the electro-magnet *A* first closes the contact *c*₁ 70 by the completion of an electric circuit similar to the one described and actuates the electro-magnet *j*, whereby the controller 2 is moved forward by one step, and then the time delay contact *c*₂ is closed, so that the magnet *B* is energized by a circuit consisting of the contact *c*₂, 75

the line 34, the coil of the magnet *B*, the lines 35, 26, and 27, the battery *C*₁ and the lines 22, 23, and 36; the magnet *B* closes the contact *c*₃. Then the magnet *g* is energized by a circuit consisting of the closed contact *c*₃, the line 33, the 5 magnet *g*, the lines 33', 26, and 27, the batteries *C*₁ and *C*₂, and the lines 28, 29, and 40, and moves the roller 4 along the stud 3 by a selective lever *m* so as to transfer it to the 'dash' mark track. Consequently, upon receipt of the 'dash' mark by 10 this system, the magnets *A*, *j*, *B* and *g* are actuated to move the controller 2 forward by one step and at the same time to shift the roller 4 to the left from the middle position and thus transfer it to the 'dash' track. 15

Next, in case of the letter space or the termination of an incoming signal, the contact 21 of the relay *R* is kept open for a longer time than the 'space' time and, accordingly, the contact *c*₆ of the magnet *A* too is kept in a contacting condition for a similar time. Therefore, on this occasion *D* is energized by a circuit consisting of the closed contact *c*₆, the lines 37 and 38, the coil of the magnet *D*, the lines 39, 26 and 27, the battery *C*₁ and the lines 22 and 22'. The magnet 25 *D* closes the contact *c*₄, whereupon the magnet *E* is energized by a circuit consisting of the contact *c*₄, the line 41, the coil of the magnet *E*, the lines 42, 26 and 27, the battery *C*₁, the lines 22 and 22', the contact *c*₅ and the lines 37 and 37'. 30 The magnet *E* closes the contact *c*₅, and then the magnet *h* is actuated by a circuit consisting of said closed contact *c*₅, the line 43, the coil of the magnet *h*, the lines 44, 26 and 27, the batteries *C*₁ and *C*₂ and the lines 28, 29 and 45, thus removing the roller 4 to the space track or the right track and at the same time closing the contacts *a* and *b*. Then, the magnet *i* is actuated by a circuit consisting of the closed contact *a*, the line 46, the coil of the magnet *i*, the lines 46', 29 and 28, the 40 batteries *C*₂ and *C*₁ and the lines 27, 26 and 47, and moves the controller 2 forward by one step through the ratchet *W*.

In short, according to this arrangement, if the 'dot' mark is received, the controller 2 is moved 45 forward and the roller is caused to enter the middle track. Also, in case of the 'dash' mark the controller 2 is moved forward by one step, and after that the roller 4 is caused to enter the left track or 'dash track', while when it is a letter 50 space, the roller is removed with regard to the right track or the 'space' track, after which the controller is moved a step forward.

The multiple contact groups *F*₁—*F*₅ shown in Figure 6 have their respective contacts 14', 15', and 55 16' (see Fig. 3) arranged on the fixed frame so as to be able to receive the signals "SOS", the ordinary call signal, "ABC", the weather signal, "MM", the general search signal, "QC", and the alarm to sailing vessels, "TTT", as indicated in 60 Figure 5. Consequently, with a single apparatus it is possible to receive several kinds of predetermined signals. Each of these contacts consists of a stationary contact member 16 and a movable contact member having an arm 15 adapted to receive pressure from the roller 5; the contact terminals 13 connected with these contact members are connected in series in a certain order to correspond to the predetermined signals "SOS" and "ABC", so that upon the entry of the 70 roller 4 into the 'dash' track, each 'dash' contact 14' in said track is closed successively, while when it enters the 'dot' track, each contact 15' is closed. Also, when the roller has been selected to the 'space' track, each contact 16' is closed. 75

To explain this system, taking as an example the case where the distress signal "SOS" is received, the time before the arrival of the signal being equivalent to the long letter space, the electromagnets *h* and *i* are actuated to remove the roller No. 1 to the right track, as explained above with reference to Figure 6, and at the same time to move the controller 2 a step forward. Now, upon arrival of the signal "SOS", viz.

10   " . . . — — — . . . "

the controller moves forward three times for the first three 'dots' and delivers the rollers Nos. 2, 3 and 4 to the middle track, and for the next letter space transfers the roller No. 5 to the space track. With regard to the next three 'dash' marks representing the letter 'O', it advances three times and at the same time transfers the rollers Nos. 6, 7 and 8 to the 'dash' track, while for the letter space, when the electro-magnets *h* and *i* operate. 15 Therefore, the controlled roller arrangement takes the form shown in Figure 4. Accordingly, the contacts of the contact group *F*₁ are connected in series and also since the electro-magnet *h* is actuated to close the contact *b* in Fig. 6, the alarm relay *q*₁ is operated by a complete circuit consisting of the contact *b*, the line 48, the contacts connected in series in the group *F*₁, the line 49, the alarming relay *q*₁, the lines 51' and 51, the switch *K*₃, the lines 23 and 22, the battery *C*₁, and the lines 27, 26 and 53 to close the contacts *e*₁ and *n*₁ and open the contact *t*₁. That on this occasion the relay *q*₁ operates alone is evident from the difference of the arrangement of the contacts of the groups *F*₂—*F*₅ from that of the controlled rollers 20 Nos. 1—12 corresponding to "SOS".

Thus, as explained above, when "SOS" is received and the relay *q*₁ is operated, its holding circuit is completed by a circuit consisting of the auxiliary contact *e*₁, the lines 54 and 49, the relay *q*₁, the lines 51' and 51, the switch *K*₃, the lines 23 and 22, the battery *C*₁, and the lines 27, 26, 55 and 56. Thereupon the lamp *L*₁ and the buzzer *Z* are operated by a circuit consisting of a closed contact *n*₁, the line 57, the lamp *L*₁ and the buzzer 25 *Z*, which are connected in parallel, the lines 58 and 51, the switch *K*₃, the lines 23 and 22, the battery *C*₁, and the lines 27, 26, 55 and 59.

Similarly, if the signal "ABC" is received, the arrangement of the controlled roller groups coincides with that of the series contacts in *F*₂, whereby *q*₂ is operated by a complete circuit consisting of the closed contact series in *F*₂, the line 60, the relay *q*₂, the lines 61 and 51, the switch *K*₃, the lines 23 and 22, the battery *C*₁, the lines 27, 26 and 53, the contact *b* and the line 48. Thus, the contacts *n*₂ and *e*₂ are closed and *t*₂ opened. Then the relay *q*₂ is held in an operative position by the device *I*₂ and the signal lamp *L*₂ and the buzzer *Z*₂ are operated by a closed circuit consisting of the closed contact *n*₂, the line 64, the lamp *L*₂, the line 65, the buzzer *Z*₂, the line 51, the switch *K*₃, the lines 23 and 22, the battery *C*₁, and the lines 27, 26, 55 and 63.

The operating circuits of the alarm relays *q*₃, *q*₄ and *q*₅ corresponding to the signals "MM", "QC" and "TTT", respectively, may be easily traced in a similar manner.

When the switch *K*₂ is left open, the current which has entered from the aerial line *N* and has been amplified by the amplifier *M*, passes through

the switch *K*₁, the line 4, the relay *R*, the line 66, the contact *t*₅, the line 67, the contact *t*₄, the line 68, the contact *t*₃, the line 69, the contact *t*₂, the line 70, the contact *t*₁, the lines 71 and 72, the switch *K*₁, and the line 73 to earth. Accordingly, 5 upon receipt of a desired predetermined signal any of the relays *q*₁—*q*₅ operate to energize the corresponding lamp and buzzer and at the same time the coil circuit of the relay *R* is broken by one of the contacts *t*₁—*t*₅ of any of the operated relays 10 *q*₁—*q*₅, so that none but the first arrived predetermined signal is received.

In the above example, although the alarm circuit completed upon receiving, for instance, the signal "SOS" is cut off by opening the switch *K*₃, the 15 series contact in *F*₁ regains its original condition corresponding to "SOS" when the switch *K*₃ is closed again, thus completing the alarm circuit. To obviate this inconvenience, the switch *K*₃ is provided with the auxiliary contact *c*, which is 20 temporarily closed when the switch *K*₃ is opened, and the magnet *A* is temporarily energized by a circuit consisting of a contact *c*, the lines 75 and 24, the coil of the magnet *A*, the lines 23 and 22, the battery *C*₁, and the lines 27, 26, 25 and 76 to 25 close the contact *c*, whereby the magnet *j* is actuated to move the controller 2 forward by one step, thus breaking the connection of the series contact of *F*₁, so that the alarm circuit is not completed again even if the switch *K*₃ is closed again, and 30 the whole system is reset so that it is able to receive the next signal.

I claim:

1. A selector device for closing selectively one of a plurality of circuits in response to different 35 prearranged codes of dot, dash and interletter space impulses, comprising a stationary frame, a rotatable squirrel-cage type controller mounted for rotation in said frame and having studs fixed thereto, said studs being equally spaced at the 40 periphery of said controller and each having a contact roller mounted thereon slidable longitudinally thereof, partitions fixed to said frame adjacent to the path of movement of said studs forming three passageways corresponding to dots, 45 dashes and interletter spaces having entrances for said rollers, means for normally causing the rollers to be positioned to enter the dot passageway, selecting means positioned at the entrance to the passageways for moving the positioned roller to 50 cause the roller to enter either the dash or interletter space passageway, means responsive to the receipt of a dot, dash or interletter space impulse to move the controller the space from one stud to the next to successively present the rollers to the 55 selecting means, means responsive to the receipt of a dash impulse to cause the selecting means to move the then presented roller into the dash position, means responsive to the receipt of an interletter space impulse for causing the selecting 60 means to move the then presented roller to interletter space position, a plurality of groups of contacts mounted on said frame to be engaged by the rollers, said groups of contacts being each arranged with respect to the three positions capable 65 of being assumed by the rollers in accordance with the prearranged codes to which the controller is to respond and separate selecting circuits each including in series all of the contacts of the corresponding group of contacts.

2. A device in accordance with the first claim and including a receiving relay for receiving the impulses and repeating them to the selector, a circuit for said receiving relay, a separate relay included in said separate selective circuits for 75

energization each having a contact normally closed when the relay is deenergized, each of said normally closed contacts being included in series in said receiving relay circuit to thereby render the receiving relay non-responsive to further impulses and means for shunting said normally closed contacts.

3. A device in accordance with the first claim,

and including a relay in each of said selecting circuits, a locking circuit for each relay to maintain the relay energized independent of its selecting circuit and means for simultaneously opening the relay locking circuits and causing the controller to take one step forward independent of the impulse responsive means.

YOSHITO WATANABE.
